(57) **CLAIM**

The ornamental design for an electronic display device, as shown and described.

DESCRIPTION

FIG. 1 is a frontal top perspective view of an electronic display device in accordance with a preferred embodiment of the invention;

FIG. 2 is a bottom perspective view of the electronic display device of FIG. 1;

FIG. 3 is a top plan view of the electronic display device of FIG. 1;

FIG. 4 is a bottom plan view of the electronic display device of FIG. 1;

FIG. 5 is a left side elevation view of the electronic display device of FIG. 1;

FIG. 6 is a right side elevation view of the electronic display device of FIG. 1;

FIG. 7 is a front elevation view of the electronic display device of FIG. 1;

FIG. 8 is a rear elevation view of the electronic display device of FIG. 1;

FIG. 9 is a frontal top perspective view of an electronic display device in accordance with another embodiment of the invention;

FIG. 10 is a bottom perspective view of the electronic display device of FIG. 9;

FIG. 11 is a top plan view of the electronic display device of FIG. 9;

FIG. 12 is a bottom plan view of the electronic display device of FIG. 9;

FIG. 13 is a left side elevation view of the electronic display device of FIG. 9;

FIG. 14 is a right side elevation view of the electronic display device of FIG. 9;

FIG. 15 is a front elevation view of the electronic display device of FIG. 9; and,

FIG. 16 is a rear elevation view of the electronic display device of FIG. 9.

The broken lines are shown in the views for illustrative purposes only and form no part of the claimed design.
